UNITED STATES PATENT OFFICE.

JOHN R. WARREN, OF GRAND RAPIDS, MICHIGAN, ASSIGNOR TO HIMSELF, DONALD J. CAMPBELL, OF MUSKEGON HEIGHTS, MICHIGAN, CHARLES E. JOHNSON, PAUL R. BEARDSLEY, AND CARL P. DAMM, ALL OF MUSKEGON, MICHIGAN, TRUSTEES.

ENGINE.

Application filed December 24, 1920. Serial No. 432,934.

To all whom it may concern:

Be it known that I, JOHN R. WARREN, a citizen of the United States, residing at Grand Rapids, in the county of Kent and State of Michigan, have invented new and useful Improvements in Engines, of which the following is a specification.

The present invention relates to engines; and its object is to provide improved means for lubricating the rotary valve which controls the admission of the expansive or explosive fluid to the cylinder of engines; and further, to provide improved means for mounting the cylinder of such an engine in resilient relation to such a valve.

These, and any other objects hereinafter appearing are attained by, and the invention finds preferable embodiment in, the structure hereinafter particularly described and illustrated by the accompanying drawings, in which:—

Figure 1 is a side view of an internal-combustion engine embodying my invention, certain parts being broken away;

Figure 2 is a transverse vertical sectional view thereof taken on planes corresponding to line 2—2 of Figure 1;

Figure 3 is a transverse horizontal sectional view of three of the engine's cylinders taken on a plane corresponding to line 3—3 of Figure 1;

Figure 4 is a view in perspective of a bushing or sleeve surrounding the valve;

Figure 5 is a view in perspective of a block carrying three of the engine's cylinders and a portion of the valve's casing;

Figure 6 is a top plan view of a portion of said block; and

Figure 7 is a view of a portion of the lower part of one of the engine's cylinders showing its resilient mounting sectioned on a vertical plane corresponding to line 7—7 of Figures 2 and 3.

My invention, at least in its broader aspects, is applicable to engines of various kinds, but in the embodiment thereof chosen for illustration by the drawings and for detailed description in the body of this specification, my invention is shown in connection with a four-cycle type internal-combustion engine having six cylinders, 1, 2 and 3 thereof appearing in diametrical longitudinal section in Figure 1, the invention

being particularly well adapted for use in internal-combustion engines. The cylinders 55 have pistons 4, 5, 6, furnished with connecting rods 7, 8, 9 for operating the cranks 10, 11, 12 respectively, on the crank shaft or engine shaft 57. At their upper ends, the cylinders have ports 61, 62, 63 respectively for the admission of the operating fluid thereinto and for the expulsion of the products of combustion therefrom. These cylinders are supported (as hereinafter described) on the frame, designated generally 65 14, of the engine and are slightly movable relatively thereto in their longitudinal direction. The rotary valve 15 for controlling the admission of the operating fluid to the cylinders and for permitting the expulsion of the products of combustion therefrom, rotates in a bearing or valve chamber in a valve casing, designated generally 16, having openings communicating with the cylinders through the cylinders' said 75 ports respectively. This valve casing comprises two portions, being longitudinally split at least at one side, the upper or "first" portion 18 of which is supported in connection with and, as shown, forms a part of 80 the frame 14, and the lower or "second" portion 19 of which casing, adjacent the cylinders' ports, is supported in connection with and, as shown, forms a part of the cylinders. The cylinders are mounted, that 85 they may have a slight and cushioned movement relatively to the frame as above stated, by their lugs 20 bored to receive removably the studs 80 carried by stiff resilient bars 17 supported intermediately said lugs 90 by the shoulders 81 of the screw bolts 82 threaded in lugs 22 on the engine frame. These bolts may be turned to increase or diminish the resilient tension of the bars 17 by adjusting the cylinders in desired position relatively to the first portion 18 of the valve casing. By reason of this mounting the two portions 18, 19 of the valve casing 95 may be pressed toward each other (and adjustably so), and the valve casing's lower 100 or second portion 19 (or tantamount thereto, the casing's bushing 34) is yieldingly held in contact with the valve 15 itself.

To prevent leakage between the two portions of the valve casing, a bushing or sleeve 105 34 in said casing surrounds the rotary valve

and has openings 35 which register with the cylinders' ports respectively. To provide for the expansion and contraction of this bushing, it is provided with a series of slits 36 extending in the axial direction of this bushing and disposed end to end, and another similarly arranged series of slits 37, the slits of one series being in staggered relation to those of the other series, said slits 10 not registering with the joint between the casing's two portions. It will be seen that, although the rotary valve 15 (and the bushing with it) may expand through heating, it will not bind or stick in its chamber, inasmuch as the resilient bars 17 will permit the cylinders and the lower or second portion 19 of the valve casing to slightly move relatively to the frame and the casing's upper or first portion 18 and thus expand the 15 valve chamber in a vertical direction sufficiently to prevent such binding or sticking, at the same time retaining the valve sufficiently tight in its chamber, particularly in the region of the cylinders' ports, to prevent leakage. Inasmuch as valve leakage is principally occasioned by pressure in the cylinder due to the expansive fluid therein (in the case of steam engines and the like) or by the firing of the explosive fluid therein 20 (in the case of internal-combustion engines), or—and in less degree—by the "compression stroke" of internal-combustion engines, it will be seen that this very pressure is the force which tightens the valve at the very 25 time it tends to leak, and that when such pressure expends itself such tightening of the valve ceases. The valve is hollow, having longitudinally extending passages 24, 25 to which the fluid is supplied from a vent 30 26 in the block 27 carrying the cylinders, the fluid thence passing through a series of inlets 51 through the valve's wall, and to each cylinder's port through diametrically opposite openings 28, 29 in the valve's wall, the 35 products of combustion being discharged from each cylinder through diametrically opposite outlets 30, 31 through the valve's wall and into its longitudinally extending passages 32, 33 opening at the ends of the 40 valve into exhaust pipes 53. These inlets, openings and outlets through the valve's wall are so disposed angularly of the valve that the sequence of supply to and exhaust from the several cylinders is properly timed.

45 For lubricating the valve, the lower or second portion 19 of the valve casing has an inlet 90 leading to its interior so that oil may be supplied thereto from a pipe 91 leading from a suitable source of supply, as the 50 chamber in the crank casing 92, oil being forced through said pipe by suitable means (not shown) for exerting the necessary pressure. This inlet 90 opens into a channel 93 in the inner surface of the casing's 55 lower portion 19, such channel extending in

the longitudinal direction of the valve casing. The bushing 34 has a series of orifices 94, 95 spaced angularly from and preferably located below said channel 93 and inlet 90, whereby the oil may pass from said inlet 70 and channel, and between the bushing and the casing's lower or second portion to the bushing's interior to lubricate the valve. These orifices 94, 95 are preferably so spaced longitudinally of the bushing as to not register with the bushing's openings 35 into the valve's ports.

It will be seen that by the firing stroke of the engine the lower portion 19 of the valve casing being thereby pressed upwardly 80 will slightly compress the bushing 34 in a vertical direction; which bushing, being held at its upper side as by the pin or set screw 101 against rotation and being somewhat resilient, will slip at its outer surface—adjacent the channel 93 and orifices 94, 95 in the bushing's lower half—on the inner surface of the lower portion 19 of the valve casing. This slipping back-and forth, although slight, being repeated at each firing stroke 85 of the engine causes the oil to be worked between the bushing and the valve casing's lower portion, thence passing through the orifices 94, 95 to the valve itself. The oil returns to the crank case's chamber 92 95 through the passage 100.

As shown in Figure 1, the engine's crank shaft carries a skew gear 38 meshing with a skew gear 39 on the vertical shaft 40, between the third and fourth cylinders and rotatable in bearings 41 on the frame, said shaft having a skew gear 42 meshing with a skew gear 43 driving the rotary valve 15, whereby the valve is rotated by the crank shaft; the gear ratios of the skew gears being 100 such as to properly time the valve's rotation to the crank shaft's rotation. It will be seen that this arrangement and disposition of the means for rotating the valve is peculiarly compact and positive and effective in operation. A water jacket surrounds the cylinders, the water containing space being designated 44, 45, water being supplied by the pipe 46 and discharged by the pipe 47. To permit the free circulation of the water between the upper portion 44 of the water jacket and its lower portion 45, short tubes 48 are carried by either the cylinder block 27 or the frame 14 and slidably bear in the other. A compressible packing 49 is inserted at the free ends of these tubes. Openings for the cylinders' spark plugs are indicated at 50.

Various features shown in the drawings and hereinbefore described form the subject 125 matter of Patent Number 1,417,590, May 30, 1922, to myself and Alfred Brechting and are not claimed as a part of the present invention.

The invention being intended to be pointed 130

out in the claims, is not to be limited to or by details of construction of the particular embodiment thereof illustrated by the drawings or hereinbefore described.

5 I claim:

1. In an engine; a frame; a cylinder longitudinally movable relatively thereto; a rotary-valve casing comprising a first portion supported in connection with the frame, and a second portion supported in connection with the cylinder and having a port communicating with the cylinder and an oil-supplying inlet leading to said second portion's interior; a flexible bushing between the valve and the valve casing having an opening registering with said port and an orifice for the passage of oil from said inlet and between the bushing and said second portion to the bushing's interior, said orifice being spaced angularly from said inlet; a valve rotatable in said casing and adapted to open and close said port.
2. In an engine; a frame; a cylinder longitudinally movable relatively thereto; a rotary valve casing comprising a first portion supported in connection with the frame, and a second portion supported in connection with the cylinder and having a port communicating with the cylinder and a channel in its inner surface extending in the longitudinal direction of the valve casing and an oil-supplying inlet leading to said channel; a flexible bushing between the valve and the valve casing having an opening registering with said port and an orifice for the passage of oil from said channel and between the bushing and said second portion to the bushing's interior, said orifice being spaced angularly from said channel; a valve rotatable in said casing and

50 rotatable in said casing and adapted to open 40 and close said port.

3. In an internal-combustion engine; a frame; a plurality of cylinders longitudinally movable relatively thereto; a rotary-valve casing comprising a first portion supported in connection with the frame and a second portion supported in connection with the cylinders and having ports communicating with the cylinders respectively and a channel in its inner surface extending in the longitudinal direction of the valve casing and an oil-supplying inlet leading to said channel; a flexible bushing between the valve and the valve casing having openings 55 registering with said ports respectively and orifices for the passage of oil from said channel and between the bushing and said second portion to the bushing's interior, said orifices being spaced angularly from said channel; a valve rotatable in said casing and 60 adapted to open and close said ports.

4. In an engine; a frame; a cylinder; a rotary-valve casing comprising a first portion supported in connection with the frame and a second portion supported in connection with the cylinder and having a port communicating with the cylinder; a resilient bar having means for removably holding the cylinder against lateral movement thereon; threaded means intermediate the frame and 65 said bar for adjusting the bar in desired position relatively to said first portion of the valve casing.

In testimony whereof I have hereunto set my hand at Grand Rapids, Michigan, this 75 9th day of December, 1920.

JOHN R. WARREN.
